(57) **CLAIM**

The ornamental design for a pet food container as shown.

DESCRIPTION

FIG. 1 is a front, left, and top perspective view of a pet food container, showing my new design;

FIG. 2 is a rear, right, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled "9" in FIG. 2.

The broken lines and the shaded areas bounded by broken lines depict portions of the pet food container that form no part of the claimed design. The dot-dash broken lines in FIGS. 2 and 9 framing enlarged portions of the pet food container form no part of the claimed design.

1 Claim, 9 Drawing Sheets
